(57) **CLAIM**

The ornamental design for a flow meter housing, as shown and described.

DESCRIPTION

FIG. 1 is a top perspective view of the flow meter housing;

FIG. 2 is a top view;

FIG. 3 is a bottom view;

FIG. 4 is a side view (from the left side); and,

FIG. 5 is a side view (from the right side).

The dashed broken lines depict portions of the article that form no part of the claim.
